Primary Examiner — Jennifer L Rempfer*Assistant Examiner* — Derek Hugh Rebuck(74) *Attorney, Agent, or Firm* — Wolf, Greenfield & Sacks, P.C.(57) **CLAIM**

The ornamental design for a cushion with honeycomb pattern, as shown and described.

DESCRIPTION

FIG. 1 is a front perspective view of a cushion with honeycomb pattern, in accordance with the present design; FIG. 2 is a back elevational view thereof; FIG. 3 is a front elevational view thereof; FIG. 4 is a right side elevational view thereof; FIG. 5 is a left side elevational view thereof; FIG. 6 is a top plan thereof; and, FIG. 7 is a bottom plan view thereof. The broken lines are for illustrative purposes only and form no part of the claimed design.
